[57] CLAIM

The ornamental design for a housing for electric motor,
as shown and described.

DESCRIPTION

FIG. 1 is a plan view of a housing for electric motor
which embodies my new and ornamental design,
FIG. 2 is an elevational view of the right-hand end of
the housing for electric motor shown in FIG. 1,
FIG. 3 is a side elevational view of the housing for
electric motor shown in FIG. 1,
FIG. 4 is an elevational view of the left-hand end of the
housing for electric motor shown in FIG. 1, and
FIG. 5 is a perspective view taken from above and the
right in FIG. 1.

FIG. 2.FIG. 4.FIG. 5.
